(57) **CLAIM**

I claim the ornamental design for the chair, as shown and described.

DESCRIPTION

FIG. 1 is a perspective view of the chair;
 FIG. 2 is a front view of FIG. 1;
 FIG. 3 is a back view of FIG. 1;
 FIG. 4 is a top view of FIG. 1;
 FIG. 5 is a bottom view of FIG. 1; and,
 FIG. 6 is a side view of FIG. 1.
